UNITED STATES PATENT OFFICE

THOMAS H. FARRINGTON, OF STOCKTON, CALIFORNIA

BLUE FLAME GAS BURNER

Application filed March 8, 1930. Serial No. 434,336.

This invention relates to gas burners particularly intended to burn natural gas, and especially represents improvements over the structure shown in my co-pending application for patent, Serial No. 416,401, filed December 26, 1929; the present burner being of the same general character and being intended to be mounted in the firebox of a coal or wood range the same as the previous one.

10 The previous burner however was arranged so that the air was mixed with the gas only as the latter issued from the inner end of the burner, the air being taken from the supply in the firebox passing up through the grate below. This mixture created a yellow or straw-colored flame, which to some authorities is objectionable.

15 The principal object of the present invention is to modify the burner arrangement so that while the air still freely surrounds the inner end of the burner and may mix with the gas as it issues, said gas is initially mixed with air while still enclosed in the burner, so that the so-called blue flame is created. I have also arranged for the air to thus mix with the gas in such a manner that a blue flame of greater heat value will be provided than is had with the ordinary mixing device commonly used on gas burners.

20 A further object of the invention is to produce a simple and inexpensive device and yet one which will be exceedingly effective for the purpose for which it is designed.

25 These objects I accomplish by means of such structure and relative arrangement of parts as will fully appear by a perusal of the following specification and claims.

In the drawings similar characters of reference indicate corresponding parts in the several views:

Fig. 1 is a perspective view of my improved burner and its adjacent accessories.

Fig. 2 is a fragmentary longitudinal section of the burner at its outer end.

Fig. 3 is a cross section on the line 3—3 of Fig. 2.

Referring now more particularly to the characters of reference on the drawings, the burner comprises a relatively long cylindrical tubular member 1 open at one end and

provided at said end with a longitudinally extending flat and relatively wide lip 2 which is rigid with the normal lower edge of the member 1. Upstanding ribs 3 project lengthwise of the lip a certain distance from the sides of the member 1 so as to not only brace the lip but prevent air from swinging around and into the open end of the member 1 adjacent the lip and possibly causing a back draft. The opposite end of the member 1 is provided with a boss 4 of reduced size which is tapped to receive a short length of gas supply pipe 5.

The junction of the boss and the member 1 forms a shoulder adapted to bear against the inner face of the firebox door 6, which is orificed to receive the boss; said door forming a supporting bearing for the burner.

At its outer end the pipe is turnably connected to one end of a suitable pipe fitting 7, to the opposite end of which the main gas cock 8, preferably of a safety type, is connected. Disposed outwardly of the door 6 is an air intake cone 9 having a hub 10 at its inner end slidable on and removably secured to the boss 4. The pipe 5 turnably projects through the cone which at its outer end has air intake slots 11. The effective size of these slots is governed by a turnable and similarly slotted plate 12 mounted over the outer end of the cone as usual. Between the fitting 7 and the cone 9 a sleeve 13 is fixed on the pipe 5, said sleeve having a radial handle 14. This arrangement enables the burner to be readily turned so as to alter the angular setting of the lip 2 whenever desired and for the same purpose as set forth in said copending application.

The boss 4 is slotted lengthwise from its periphery toward the center and from end to end, so as to form passages 15 enclosed or covered by the hub 10, which afford communication between the interior of the member 1 and the interior of the cone. Air may therefore pass unobstructedly and around the pipe 5 from outside the cone to the interior of the burner member beyond the pipe. The outer walls of the slots or passages 15, where they project through the end wall of the burner member proper are preferably cut with an

inward slope toward the center of the burner, as shown at 15a in Fig. 2. This throws the air entering the burner directly across the path of the gas issuing from the pipe 5 and aids in forming a more intimate mingling of the air and gas.

The gas of course will not be mixed with the air while in the cone since the pipe 5 is continuous from outside the cone to the burner boss. The air passages 15 terminating in the burner at the inner termination of the gas-feed passage, the air will pass into the burner simultaneously with the gas and will be immediately deflected across the path of the entering gas. This arrangement causes a very efficient mixing of the gas and air and creates, at the outer end of the burner, the desired blue flame having great heating intensity.

To dismount the burner from the firebox it is only necessary to loosen the set-screw 16 which binds the air intake cone to the burner boss, and remove the burner by drawing the same inwardly of the door so that the boss clears the same.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A gas burner including a tubular member open at one end, a boss having longitudinal passages projecting from the opposite end of the member and with which said member at said end forms an outwardly projecting shoulder, a gas supply pipe fitted into one of the boss-passages, and an air-intake cone, open at its outer end, slidably engaging the boss and adapted to be adjustably clamped in place thereon.

2. A gas burner including a tubular member open at one end, a boss projecting from the opposite end of the member and comprising a longitudinally bored central portion and longitudinally extending ribs radiating therefrom, a gas supply pipe connected to the central portion of the boss, and an air intake cone comprising an open-ended portion in front of the boss and a sleeve to slidably engage the outer ends of the boss ribs and thereby form an outer closure for passages provided between the ribs.

In testimony whereof I affix my signature.

THOMAS H. FARRINGTON.
